UNITED STATES PATENT OFFICE.

ERWIN A. BURKE, OF CLEVELAND, OHIO.

SOLE AND WELT.

No. 802,494.

Specification of Letters Patent.

Patented Oct. 24, 1905.

Application filed July 19, 1904. Serial No. 217,226.

To all whom it may concern:

Be it known that I, ERWIN A. BURKE, a citizen of the United States, residing at Cleveland, in the county of Cuyahoga and State of Ohio, have invented new and useful Improvements in Soles and Welts, of which the following is a specification.

This invention relates to soles and welts for shoes, and particularly to the means by and 10 the manner in which an outer sole is fastened to a welt.

The object of the invention is to remove a defect incident to the present method of attaching the outer sole to the welt, and a further object is to save labor and reduce cost of manufacture.

In the making of welt shoes it is customary to skive or thin the ends of the welts down to a point. The object of this is to make a 20 smooth clean job by causing the ends of the welt to gradually merge into the upper surface of the outer sole at or near the heel portion thereon. In cutting down the ends of the welt and sewing the sole to the same 25 the thinness of the welt creates a liability of the thread to pull through the welt for the first two or three stitches, and the subsequent working of the shoe in walking is liable to pull through still more of these stitches, and 30 in time the ends of the welt become detached from the sole, leaving an opening. Repeated efforts have been made to devise a means whereby the ends of the welt would be prevented from becoming unstitched or loose, 35 while preserving the good appearance of the parts. To remedy the defect indicated, I make a channel across or recess in the shank of the outer sole before it is sewed to the welt. This channel or recess receives the 40 ends of the welt, which, instead of being skived down, are left at their original thickness. The channel or recess has at the heel end a depth equal to the thickness of the leather used in the welt, and the channel is 45 tapered or inclines upwardly and forwardly until it comes to the natural surface of the leather. To give a neat job, the channel should be at least three-fourths of an inch wide, gradually decreasing in depth forwardly, or from the heel toward the toe. As 50 said before, the welt is not thinned down at the ends, but is left its original thickness, and when placed in position the ends of the welt come against the rear shoulder or edge of the 55 channel or depression, and when stitched on the machine the threads go through the en-

tire thickness of the welt. The sole is of sufficient thickness to hold the threads without danger of pulling out, and so are the ends of the welt, and there is no chance of 60 the threads pulling out of either, as in the old method, wherein, as said before, the ends of the welt are thinned down to an edge. Also by my invention the labor of skiving the ends of the welt is dispensed with, thereby 65 saving labor and reducing the cost of manufacture. The ends of the welt being of the original thickness—that is, the same thickness as the rest of the welt—a stronger construction results, and there is no danger of the 70 shoe opening up between the welt and the outer sole in consequence of wear. Full strength of the welt is retained and a neater and more durable job is produced.

The invention is illustrated in the accompanying drawings, in which—

Figure 1 is a plan view of the back or top of an outer sole before the same is applied to the welt. Fig. 2 is an edge view of the same. Fig. 3 is a plan view of the outer sole with 80 the welt in place, the upper and insole being removed for the sake of clearness. Fig. 4 is an edge view thereof. Fig. 5 is a plan view illustrating a modification.

In the drawings the outer sole is indicated 85 at 6, and 7 indicates a channel cut across the same in the top or back thereof. At the rear edge this channel has a square or blunt shoulder 7^a, and the channel gradually decreases upwardly and forwardly therefrom until it 90 merges with the surface of the sole at 7^b.

The welt is indicated at 8 and is first sewed to the upper and insole. The outer sole is then sewed to the welt, with the ends thereof fitting or abutting against the shoulder 7^a. These 95 ends are of the same thickness as the body of the welt, and the channel 7 is of proper depth to receive the same. The sole is stitched to the welt, the stitches indicated at 9 covering the joint between the ends of the welt and the 100 sole at 7^b. It will be seen that by retaining the original thickness at the ends of the welt the threads are not liable to pull out, as when the ends are skived down to a sharp edge.

In the modification shown in Fig. 5 instead 105 of cutting a channel across the sole triangular incisions or depressions are cut in the sole on each side thereof, as indicated at 10. These incisions have a shoulder at the rear end and taper upwardly and forwardly in similar manner to the channel 7, and the welt is let into these depressions and sewed through in the 110

same manner as above described with respect to the other construction.

It is much less labor to cut a channel 7 across the sole than it is to skive down the ends of 5 the welt. The invention therefore results in a saving of labor and time in addition to the other advantages referred to.

What I claim as new, and desire to secure by Letters Patent, is—

- 10 1. In a welt shoe, an outer sole having in the shank thereof a recess of increasing depth toward the rear of the sole, adapted to receive the ends of the welt.
2. In a shoe, a welt with blunt ends, and an 15 outer sole sewed thereto having a depression

in the shank, of increasing depth toward the rear, into which depression the ends of the welt fit.

3. In a shoe, an outer sole having a depression in the shank with a shoulder at the rear, 20 and a welt to which the said sole is sewed, said welt having blunt ends which fit in the depression and abut against said shoulder.

In testimony whereof I have signed my name to this specification in the presence of two sub- 25 scribing witnesses.

ERWIN A. BURKE.
